UNITED STATES PATENT OFFICE.

RICHARD F. ELBURN, OF CHESTERTOWN, MARYLAND.

GAME-BOARD.

No. 818,237.

Specification of Letters Patent.

Patented April 17, 1906.

Application filed March 19, 1904. Serial No. 198,990.

To all whom it may concern:

Be it known that I, RICHARD FRANKLIN ELBURN, a citizen of the United States, residing at Chestertown, in the county of Kent and State of Maryland, have invented a new and useful Improvement in Game-Boards, of which the following is a specification.

My invention relates to an improvement in game-boards, its object being to provide a device which shall prove amusing and entertaining as well as instructive.

To these ends my improvement consists in certain novel features hereinafter fully described, and pointed out in the claim.

15 In the drawings, Figure 1 is a top plan view of a box embodying my invention. Fig. 2 is a vertical section taken on line 2 2 of Fig. 1. Fig. 3 shows one of the counter-pegs. Fig. 4 represents one of the playing-pegs or 20 men.

In carrying out my invention I make my apparatus preferably in the form of a box A, the cover of which may be hinged, or it may be a simple slip-cover. The top of the cover 25 A' has delineated upon it one or more (preferably two) concentric circular lines a , and between said lines a concentric circular row of holes a' is made, as shown in Fig. 1. At the upper portion of the concentric circles is 30 made a suitably-shaped figure a^2 , which has in its center one of the holes before referred to. At the lower portion of the circles is shown a blank space a^3 , which designates the starting-point of the concentric row of holes. 35 An equal number of holes is disposed at each side of the spaces referred to, and at preferably every fifth hole the number is placed so that the totals can be easily counted.

Two vertical chords b and two horizontal 40 chords c , of substantially equal length, intersecting each other are drawn from the inner circle, forming nine inclosures $c' c'$, within each of which are the holes c^2 . Each of the spaces formed by the inner circle and the intersecting chords have delineated on their 45 faces a suitable number, as shown.

The game-pieces used are twelve in number—six of one color and six of a contrasting color. Of each set of six pieces one (designated as B) is larger than the others and is used as a counter. The other five, b' , are used in playing the game to be placed in the holes.

The game is played by two persons, each having six pieces, all the pieces of each player

being of the same color. The game is played 55 by one player starting and putting one piece or peg in one of the holes within the spaces c' , the object being to get the pegs in the highest-numbered holes and also to get his pegs in a row either in a straight line or diagonally. 60 As soon as one of the players has succeeded in placing three of his men in a row he adds the numbers in said three spaces and places his counter that distance around the circle. The other player makes no count at all. The 65 small men are removed at once, and the play proceeds until one of the players reaches No. 30, or the goal, each player starting at the bottom at the center and counting upwardly to the top. The player who first reaches the 70 30-hole, or goal, wins the game.

It will be seen that I provide a game which will be pleasing and interesting and also an aid in teaching children how to count. The holes in the box-cover may extend entirely 75 through the same. The game-pieces or men can be made in any desired shape or configuration, the only requisite being that each set of six should be of contrasting colors.

While the general rules of playing will be as 80 above stated, yet it is obvious that different rules for playing may be devised—such, for instance, as in the event that neither player succeeds in getting three of his pegs in a row the player who has one of his men in the line 85 of spaces comprising the figure sought scores five and moves his counting-peg around the circular row of holes that distance.

While one of the main objects of the game is for a player to get his pegs in the highest-numbered holes within the spaces c' , yet it will be observed that a player can by exercising skill and judgment in putting his peg in low-numbered spaces prevent or block his opponent from getting his pegs in high-numbered rows.

Having thus described my invention, what I claim as new, and desire to secure by Letters Patent, is—

A game apparatus consisting of a suitable 100 base having delineated thereon a plurality of intersecting horizontal and vertical lines forming a plurality of spaces, a value-numeral delineated on the surface of each space, a circle inclosing the vertical and horizontal lines, 105 each space provided with a peg hole or socket, a row of peg-holes beginning below the lower central space at each side of the vertical

center of the same and extended upwardly in an arc to the side of the vertical center of the upper central space, a peg-hole located above the upper space at its vertical center, said peg-hole forming a continuation of the two side arcs of holes and being common to each, two sets of game-pegs of contrasting

colors, each set consisting of a specified number of small pegs and one large or registering peg.
